(57) **CLAIM**

The ornamental design for a stake holding tool as shown and described.

DESCRIPTION

FIG. 1 is a perspective view of a stake holding tool showing my new design.

FIG. 2 is a bottom plan view of the stake holding tool of FIG. 1.

FIG. 3 is a top plan view of the stake holding tool of FIG. 1.

FIG. 4 is a first side elevation view of the stake holding tool of FIG. 1.

FIG. 5 is a second side elevation view of the stake holding tool of FIG. 1.

FIG. 6 is a first end view of the stake holding tool of FIG. 1.

FIG. 7 is a second, opposite end view of the stake holding tool of FIG. 1.

FIG. 8 is a perspective view of a stake holding tool in accordance with a second embodiment.

FIG. 9 is a bottom plan view of the stake holding tool of FIG. 8.

FIG. 10 is a top plan view of the stake holding tool of FIG. 8.

FIG. 11 is a first side elevation view of the stake holding tool of FIG. 8.

FIG. 12 is a second side elevation view of the stake holding tool of FIG. 8.

FIG. 13 is a first end view of the stake holding tool of FIG. 8; and,

FIG. 14 is a second, opposite end view of the stake holding tool of FIG. 8.

The broken lines in the drawings illustrate portions of the stake holding tool which form no part of the claimed design.

1 Claim, 8 Drawing Sheets
